(57) **CLAIM**

The ornamental design for a vehicle sidestep, as shown and described.

DESCRIPTION

FIG. 1 is a top perspective view of a vehicle sidestep, showing my new design.

FIG. 2 is a front elevational view of the vehicle sidestep.

FIG. 3 is a rear elevational view of the vehicle sidestep.

FIG. 4 is a left side elevational view of the vehicle sidestep.

FIG. 5 is a right side elevational view of the vehicle sidestep.

FIG. 6 is a top plan view of the vehicle sidestep; and,

FIG. 7 is a bottom plan view of the vehicle sidestep.

The vehicle sidestep is shown with a symbolic break in its length. The appearance of any portion of the article between the break lines forms no part of the claimed design.

The broken lines in the drawings depict portions of the vehicle sidestep that form no part of the claimed design.
